CONCEALED BED

Edward E. Woller, Kenosha, Wis., assignor to
 Simmons Company, Kenosha, Wis., a corpora-
 tion of Delaware

Application May 16, 1946, Serial No. 670,168

9 Claims. (Cl. 5—147)

1

This invention relates to an improvement in a concealed bed, that is to say, a bed which, when not required for use, is concealed within a cabinet from which it may be withdrawn and extended for use.

The main objects of the invention are to provide a bed of the character indicated which may be stored or concealed within a cabinet which occupies a minimum of floor space; and to provide a bed which may be quickly and easily moved to either concealed or extended position by practically any person without previous extensive instruction.

Other objects and advantages of the invention will be understood by reference to the following specification and accompanying drawings (4 sheets) wherein there is illustrated a bed structure embodying a selected form of the invention.

In the drawings:

Figure 1 is a perspective illustrating the improved bed structure in its extended or operative position;

Figure 2 is a plan of an end portion of the extended bed structure;

Figure 3 is a fragmentary plan section corresponding to a portion of Figure 2 but showing the parts on a larger scale and in greater detail;

Figure 4 is an end view of the structure in extended position;

Figure 4a is an end view corresponding in part to a portion of Figure 4 and showing the continuation of said portion of Figure 4;

Figure 5 is an end view corresponding to Figure 4 but showing the bed in folded or concealed position;

Figure 6 is a vertical section on the line 6—6 of Figure 4;

Figure 7 is a section on the line 7—7 of Figure 4;

Figure 8 is a section on the line 8—8 of Figure 4;

Figure 9 is an elevation of a portion of the mechanism shown in Figure 8; and

Figure 10 is an elevation of another portion of the mechanism shown in Figure 8.

The bed structure herein illustrated comprises a mattress supporting frame 1 which is mounted so as to be encloseable in a suitable cabinet 2 from which it may be extended to the horizontal bed position in which it is illustrated in Figure 1. The bed frame structure comprises an upper tubular frame 3 and a lower tubular frame 4, these frames being generally horizontally disposed and spaced vertically from each other (in bed position) a predetermined, fixed distance by means of struts or spacers 5. The upper tubular frame 3 has its front side bar provided with a

centrally offset portion 6 which engages the central portion of the front side bar of the lower frame member 4. The rear side member of the upper frame 3 is indicated at 7 and it is a tube of somewhat larger diameter than the tubing forming the balance of said upper frame member. Said enlarged rear side member 7 is joined to the end portion of the upper frame so as to provide open ends for purposes which will presently appear.

The cabinet 2 may conveniently be of sheet metal and angle iron construction, embodying sheet metal ends 8—8 having peripheral flanges 9 extending inwardly from the end panels, a lower front wall portion 10, a front door or cover panel 11 hinged as indicated at 12 to the upper edge of the front wall portion 10, and a top wall or panel 13 hinged as indicated at 14 to the upper rear edge of the cabinet structure. A suitable folding brace 15 is provided for holding the top wall or cover 13 in the open position in which it is illustrated in Figures 1 and 3.

When the bed is in its extended position as shown in Figures 1 and 4, it is supported at its ends by means of arms such as represented at 16, said arms being pivotally mounted as shown at 17 on bearing or mounting blocks 18 which are bolted to the respective end walls as indicated at 19. The pivot pins 17 are preferably rigidly secured to the respective arms 16 and mounted for rotating movement in the bearing blocks 18. Free turning screw threading may be employed for the pivot mounting as indicated, to thereby control endwise shifting of the structure. It will be apparent that the rotary movement is of the order of 90° so that there is but little endwise shifting occasioned by the employment of screw threaded pivots. The arms 16 have angle members 20 and 21 welded or otherwise secured to their opposite ends, said angle members each having a horizontally inwardly extending leg underlying the lower frame portion 4 of the bed structure. The bed structure is slidably supported by said angle members 20 and 21 and the end members of the lower frame 4 are preferably provided with suitable wear plate elements 22 suitably secured to the frame.

The outer end portion of the bed structure is supported in its extended position by means of the front panel 11 which acts as a strut or brace between the upper edge of the cabinet front wall portion 10 and the lower frame portion 4 of the bed structure. The end members of the lower frame 4 are each equipped with depending ears or studs such as represented at 23 for engage-

ment with the free end of the panel 11 so that any downward movement of the outer portion of the bed structure will be resisted by the brace-like front panel 11. The outer portion of the front panel is movably connected to the outer portion of the bed frame structure at each end by means of a link 24 pivoted as shown at 25 to the front panel 11 through the agency of a suitable bracket and provided at its other end with a roller 26. The roller 26 is movable between upper and lower tracks 27 and 28 (Figures 4 and 7) which are carried by a plate 29 suitably secured to the tie members 5 as indicated.

It will be seen that, from the bed position of the bed frame as illustrated in Figures 1 and 4, the bed structure may be rocked upwardly about the pivot 17 while also being slid inwardly over the angle brackets 20 and 21 of the pivot arms 16 and downwardly into the cabinet.

For controlling such inward and downward movement of the bed structure and for counterbalancing its weight, a counterbalancing spring arrangement is provided in the enlarged inner or rear side member 7 of the upper frame structure. The details of this counterbalancing arrangement are shown in Figures 8, 9, and 10.

Said counterbalancing spring structure within the frame member 7 comprises a helical coil spring 30 within the tube 7 and around a shaft 31. The shaft 31 is rotatably supported within the tube 7 through the agency of suitable ball bearings indicated at 32—32, the outer races of which fit in suitable pockets or recesses formed in end members 33 and 33a which have hub portions projecting into the ends of the tube 7 so as to be properly positioned relative to the tube. Collars represented at 34—34 have hub portions which fit around the outside of the end portions of the tube 7 and flange portions which provide for screw attachment thereof to the end members 33 and 33a as indicated at 35. The members 33 and 34 at each end of the tube 7 constitute, in effect, end fittings which are clamped in fixed position on the ends of the tube 7. If necessary to secure stronger anchorage of the end fittings to the tube 7, the members 34 may be brazed or welded to the tube 7.

The spring 30 has one end anchored to the tube 7 through the agency of the fitting 33 for which purpose the latter has its hub portion extended somewhat and provided with an annular slot 36 and a transverse groove 37 for receiving a hooked end portion 38 of the spring.

The other end of the spring 30 is similarly anchored to the shaft 31 which has secured to it a collar or bushing 39 provided with an annular recess 40 and a transverse slot 41 to receive a hooked end portion 42 of the spring. As represented in Figures 9 and 10, the spring end hooks are in opposite directions so that counter-clockwise rotation of the shaft 31, when viewed from the right-hand ends of Figures 8, 9, and 10, would wind the spring about the shaft 31, the other end of the spring being anchored against rotation as already described. In one practical embodiment of the invention, the spring 30 extends for about two-thirds of the length of the bed. To provide additional support for the shaft 31 within the tube 7 and support for the latter, one or more bushings such as indicated at 43 may be provided at suitably spaced points within that portion of the tube 7 which is not occupied by the described spring structure, such supporting bushings may be anchored to the tube 7 by one or more screws as represented at 44.

At each end of the shaft 31 there is provided a gear or pinion 45 between outer and inner flange plates 46 and 47, respectively. The flange plate 47 may be free to rotate on the shaft 31, but the flange plate 46 and gear 45 are suitably keyed to the shaft so as to rotate as a unit with the shaft. Any suitable means may be provided for keying the outer flange plate 46 and gear 45 to the shaft, screw 48 threaded into tapped openings partially in the shaft and partially in the flange plate and gear being employed in this instance. The outer flange plates 46 and gears 45 are also preferably united by being riveted together as indicated at 49.

15 The gears 45 are arranged to mesh with vertically disposed rack bars 50 mounted in each end member 8 of the cabinet. Said rack bars 50 may conveniently be mounted by being bolted as indicated at 51 to one flange of angle iron 52 which is suitably secured to the end panel 8. Another angle member 53 is disposed opposite to angle 52 and secured to said end panel 8 in such spaced relation to the angle 52 as to cooperate therewith to form a vertical guide or track for 20 receiving the inner flange member 47 as best shown in Figure 3. The flange member 47 is thus operative to guide vertical movement of the inner edge of the bed structure within the cabinet and to maintain the gear 45 in mesh with the rack 25 bar 50.

When the bed structure is to be closed or folded to concealed position, it is elevated at its outer side, the structure being rocked on the pivot 17 thereby causing the gear 45 at each end to roll 30 downwardly on its rack 50. Such rotary movement of the gear is, of course, transmitted to the shaft 31 and fittings to one end of the spring 30 so that the latter will be wound up as the inner side of the bed structure moves downwardly within the cabinet. The spring 30 is selected to be of such strength that it will provide adequate counterbalancing for the bed structure so that its downward movement within the cabinet will be properly cushioned to prevent damaging of the structure incident to the closing thereof. Said spring furthermore supplies lifting power which is almost sufficient to move the bed structure upwardly from its concealed position as shown in Figure 5. Slight lifting force 35 manually applied to the outer or upper side portion of the bed structure when in its concealed position as shown in Figure 5 will result in upward movement of the bed structure.

A coiled tension spring 54 is stretched between 40 a bracket 55 secured in the lower front corner portion of the cabinet and an extended inner end portion 56 of the arm 16 so as to serve, during the initial portion of the folding movement of the bed structure, to counterbalance the 45 weight of the extended bed to facilitate closing thereof. When the bed is in its extended position, the spring 54 is stretched to its maximum extent so that it offers its greatest bed lifting force at that time. As the bed structure approaches its folded or concealed position, the 50 force of the spring 54 is reduced. It offers but little if any downward pull on the bed structure within the frame; whatever slight pull may be present in the spring 54 in the folded position of the bed, as shown in Figure 5, is adequately offset by the lifting force of the spring 55 in the rear member 7 of the upper frame. Hence, when unfolding the structure, the spring 54 does not materially resist the unfolding movement.

When the bed is to be unfolded, the cover 13 is opened from the position shown in Figure 5 to the position shown in Figure 4. The cover 13 is provided with one or more sockets such as indicated at 57 for receiving locking pins 58 which project from the upper edge of the front panel 11. When the cover is opened, the panel 11 is released for outward folding movement. However, the bed structure 1 is first raised vertically without any material outward swinging movement, such upward movement being effected primarily by the force of the wound-up spring 30, but aided by slight but sufficient manual force. As soon as the axis of the rear side portion 7 of the bed structure is lifted sufficiently, i. e., to a point about in the horizontal plane of the axis of the hinges 12, upward unfolding movement may be started, such upward unfolding movement being also accompanied by relative sliding movement of the bed structure outwardly relative to the front panel 11 so that the bed structure will project beyond the free edge of the front panel 11 as represented in Figures 4 and 4a as compared with its retracted position shown in Figure 5.

A limited amount of substantially vertical movement of the bed structure required for initiating unfolding thereof is a desirable feature for the reason that it substantially prevents unintentional and accidental opening of the bed. The bed structure is itself made particularly adaptable to installation on ships and railroad cars, the normal movements of which might tend to unfold a bed structure which is less securely held in its closed position. It may be observed that the locking effect referred to is present even though the cover member 13 is open.

Any suitable mattress 59 may be positioned within the bed frame, the mattress being supported by suitable means such as lengthwise extending slats 60 which may be spring-suspended between the opposite end members of the lower frame structure as indicated at 61. The mattress may be fastened in place in the supporting structure by means of flexible fabric straps 62 suitably secured at their ends to the opposite side members of the top frame 3.

Pivottally supported arms 16 may advantageously be tied together at their outer free ends by means of a longitudinally extending tie strap 63 which may be secured at its ends by riveting or otherwise to the angle members 20 at the outer ends of the said arms.

In the closed position of the bed, the roller 26 may engage a link 64 extending between the outer or upper ends of the tracks 27 and 28. Such engagement serves to limit downward movement of the bed structure and also to insure that the bed structure is held tightly against the front panel 11, the latter resulting from the link mounting of the roller 26 on the panel. This will serve to prevent the bed structure from shifting within the cabinet so that rattling noise will be avoided thereby when the structure is embodied in a ship or railroad car. The lower end portion of the bed structure in its closed position is, of course, held against shifting by the fit of the flange 47 between the guides 52 and 53. The employment of a screw threaded pivot 17 as above mentioned also aids in the prevention of rattling.

Various changes in the described structure may be made without departing from the invention.

I claim:

1. A bed of the class described comprising a 75

support, a bed frame, and means slidably and swingably mounting said bed frame on said support and adapted to permit a swinging of said bed frame relative to said support only when said bed frame has been shifted vertically into a predetermined position above its vertically-disposed folded position.

2. A bed of the class described comprising a support, a bed frame, means for slidably and pivotally supporting said bed frame on said support, and a vertically shiftable pivotal connection between said bed frame and said support, said means on said connection co-acting to permit a swinging of said bed frame relative to said support only when said bed frame has been shifted vertically a predetermined distance above its vertically-disposed folded position.

3. A bed of the class described comprising a support, a bed frame, means slidably and swingably mounting said bed frame on said support and adapted to permit a swinging of said bed frame relative to said support only when said bed frame has been shifted vertically a predetermined distance above its vertically-disposed folded position; and other means for counterbalancing the downward vertical movement of said bed frame on said support.

4. A bed of the class described comprising, a support, a bed frame, a vertical track on said support, a pivotal connection between said bed frame and said track reciprocable on said track, and means on said support in forwardly spaced relation to said track for slidably and pivotally supporting said bed frame, said means and connection co-acting to permit a swinging of said bed frame relative to said support only when said bed frame has been shifted vertically a predetermined position above its vertically-disposed folded distance.

5. A bed of the class described comprising, a support, a bed frame, a vertical track fixed on said support, a roller journaled on said bed frame and confined to reciprocal movement along said track, and an arm pivoted on said support forwardly and intermediate the ends of said track and slidably supporting said bed frame, said track-confined roller and said pivoted arm co-acting to permit a swinging of said bed frame relative to said support only when said bed frame has been shifted vertically into a predetermined position above its vertically-disposed folded position.

6. A bed of the class described comprising, a support, a bed frame, a vertical track fixed on said support, a roller journaled on said bed frame and confined to reciprocal movement along said track, an arm pivoted on said support forwardly and intermediate the ends of said track and slidably supporting said bed frame, said track-confined roller and said pivoted arm co-acting to permit a swinging of said bed frame relative to said support only when said bed frame has been shifted vertically into a predetermined position above its vertically-disposed folded position, a rack disposed along said track, a gear associated with said roller and engaging said rack, and a torsion spring arranged between said gear and bed frame for counterbalancing a portion of the weight of said bed frame during its movement into and out of its vertically-disposed folded position.

7. A bed of the class described comprising, a support, a bed frame, a vertical track fixed on said support, a roller journaled on said bed frame and confined to reciprocal movement along said

track, an arm pivoted on said support forwardly and intermediate the ends of said track and slidably supporting said bed frame, said track-confined roller and said pivoted arm co-acting to permit a swinging of said bed frame relative to said support only when said bed frame has been shifted vertically a predetermined distance above its vertically-disposed folded position, a rack disposed along said track, a gear associated with said roller and engaging said rack, a torsion spring arranged between said gear and bed frame for counterbalancing a portion of the weight of said bed frame during its movement into and out of its vertically-disposed folded position, and a tension spring interposed between the inner end of said pivoted arm and said support and adapted to counterbalance at least a portion of the weight of said bed frame as it swings into and out of its horizontally extended bed position.

8. A bed of the class described comprising an open top cabinet, a door hinged along its lower edge to provide an outwardly swingable front for said cabinet, a bed frame mounted on said cabinet for movement between a vertically-disposed folded position and a horizontally extended bed position, a track arranged along the back of said cabinet, a pivotal connection between said bed frame and said track reciprocable along said track, means on said cabinet intermediate the ends and forwardly of said track for pivotally and slidably supporting said bed frame, said means and connection co-acting to permit a swinging of said bed frame relative to said cabinet only when said bed frame has been shifted vertically a predetermined distance above its vertically-disposed folded position, said door being swingable with said frame, and means on the outer edge of said door adapted to engage said bed frame to provide support therefor in its horizontally-extended bed position.

9. A bed of the class described comprising an open top cabinet, a door hinged along its lower edge to provide an outwardly swingable front for said cabinet, a bed frame mounted on said

cabinet for movement between a vertically-disposed folded position and a horizontally extended bed position, a track arranged along the back of said cabinet, a pivotal connection between said bed frame and said track reciprocable along said track, means on said cabinet intermediate the ends and forwardly of said track for pivotally and slidably supporting said bed frame, said means and connection co-acting to permit a swinging of said bed frame relative to said cabinet only when said bed frame has been shifted vertically a predetermined distance above its vertically-disposed folded position, means interconnecting the free edge of said door with said frame for effecting movement of said door between a closed and openly inclined position as an incident to the swinging of said bed frame into and out of its horizontally-extended bed position, and means on the outer edge of said door adapted to engage said bed frame to provide support therefor in its horizontally-extended bed position.
